UNITED STATES PATENT OFFICE.

EDWIN N. LIGHTFOOT, OF NEW YORK, N. Y., ASSIGNOR TO THE CUTLER-HAMMER MFG. CO., OF MILWAUKEE, WISCONSIN, A CORPORATION OF WISCONSIN.

ELECTRICALLY-HEATED LAUNDRY-IRON.

1,364,122.

Specification of Letters Patent.

Patented Jan. 4, 1921.

Application filed September 28, 1917. Serial No. 193,648.

To all whom it may concern:

Be it known that I, EDWIN N. LIGHTFOOT, a citizen of the United States, residing at New York, in the county of Bronx and 5 State of New York, have invented new and useful Improvements in Electrically-Heated Laundry-Irons, of which the following is a full, clear, concise, and exact description, reference being had to the accompanying 10 drawing, forming a part of this specification.

This invention relates to electrically heated laundry irons and other devices and more particularly to automatic cutoff means 15 therefor.

Various means have heretofore been proposed for cutting off the current supply to such devices under given maximum temperature conditions, but it is believed that such 20 means have proven unreliable in service and unduly complicated and expensive.

The present invention therefore has among its objects to provide an electrically heated device with thermally controlled cutoff means which may be formed of a few 25 simple and rugged parts and which will be positive and reliable in operation and also practically instantaneous in action.

A further object is to provide means of 30 the character stated which will be sensitive to the temperature conditions of that part of the controlled device which is subjected to the maximum amount of heat and which will be protected against injury by careless 35 handling of the controlled device.

A further object is to provide means of 40 the character stated capable of ready application to existing irons and other structures and readily renewable either in part or as a whole.

Other objects and advantages will herein-after appear.

In the accompanying drawing,

Figure 1 is a vertical sectional view of an 45 embodiment of the invention as applied to a conventional form of laundry iron; while

Figs. 2 and 3 are fragmentary views showing slightly modified constructions.

Referring to Fig. 1 of the drawing, the 50 same discloses an iron having the usual shoe 1, casing 2, handle support 3 and heating element 4 electrically connected with a pair of contact pins 5 projecting from the casing 2 and arranged for engagement by a plug 6, 55 the latter being connected with a source of

current by means of a flexible conductor 7. The cutoff device comprises, in general, a reflexed spring member 8 anchored at one end and having its opposite end engaged beneath the plug 6, said spring being normally tensioned and restrained by a rod 9 anchored to the body of the iron, and being adapted when relieved of such restraint to throw off the plug 6 from the pins 5 thereby by interrupting circuit to the heating element. 60

More particularly the spring 8 is carried within suitable slots 10, 10 of the handle support 3, the fixed end of said spring being anchored within a suitable socket 11 in said 70 support, while its free end 12 is bent downwardly to fit between the lower end of the plug 6 and the shoulders 13 of the contact pins 5. The spring 8 is further offset at 14 to pass the upper end of the rod 9, said rod 75 and spring being restrained against lateral separation by a clip 15, while a nut 16 is screwed upon said rod beyond the spring for restraining movement of the latter axially of the rod. In practice the nut 16 is preferably provided with a heat insulating covering 17 to facilitate adjustment thereof when the iron is in use. 80

The lower end of the rod 9 is provided with a head 18 and surrounded immediately 85 above said head by a flat fusible ring or washer 19 countersunk in the shoe 1 and forming with said rod 9 a renewable fusible element or cartridge readily insertable within the iron. The ring 19 is composed of 90 metal or alloy having a relatively low fusion temperature, whereby upon excessive heating of the iron, said ring is adapted to soften and release the rod 9, whereupon the spring 8 will act to interrupt the circuit of the 95 heating element in the manner described.

The rod 9 extends upward through a vertical passage 20 in the body of the iron, said passage being counterbored at 21 within the shoe 1 to receive the ring 19 which is 100 adapted to seat against a shoulder 22, being held in such relation by the tension of the spring 8. A sleeve 23, is also located in the passage 20 and surrounds the rod 9, the bore of said sleeve being of sufficient diameter to 105 permit ready passage of the head 18 therethrough.

In the construction illustrated in Fig. 2, the sleeve 23^a is preferably of metal and is extended downward and provided with an 110

annular flange 24 adapted to seat against the shoulder 22 for retention against upward displacement. The bore of said sleeve is of but slightly larger diameter than that of the rod 9^a, said members being united at their lower ends by a relatively thin film 25 of fusible material and constituting jointly a renewable element or cartridge which is readily insertible within the body of the iron.

In the construction illustrated in Fig. 3, the sleeve 23^b is of substantially uniform exterior diameter throughout its length, being exteriorly threaded at its lower end and 10 adapted to be screwed down within a socket 26 provided within the upper surface of the shoe 1. Said sleeve is furthermore of sufficient length to project above the body of the iron for facilitating assembly therewithin. Thus in each case the fusible element is located within the zone of maximum temperature of the iron, *i. e.*, within the shoe, and the cartridge as a whole is readily insertible and renewable.

As will thus be apparent the cartridge may be quickly and easily renewed following softening of the fusible material thereof and in this connection it is to be noted that renewal of the cartridge is preferable 20 to repair thereof since repeated fusing of the fusible material tends to oxidize the same, with the result of varying its fusing temperature and hence varying the sensitivity of the cutoff means as a whole. Also, as will be apparent, the cartridges 25 illustrated might be arranged in other relations with respect to the controlled device and readily adapted to use externally on devices not provided with internal sockets therefor.

What I claim as new and desire to secure by Letters Patent is:

1. The combination with an electrically heated device, of circuit control means therefor tending to disconnect the same from circuit and restraining means for said former means to effect release thereof under given thermal conditions of a working portion of said device, said restraining means including a fusible element located within such portion of said device and detachably secured therein for ready renewability from without said device.

2. The combination with an electrically heated device, of circuit control means therefor tending to disconnect the same from circuit and restraining means for said former means to effect release thereof under given thermal conditions of a working portion of said device, said restraining means including a fusible element releasably secured within such portion of said device for ready renewability and a member secured to said device by said fusible element, said fusible element being rela-

tively small in cross section and when fused permitting unrestricted movement of said member.

3. The combination with an electrically heated device, of circuit control means therefor tending to disconnect the same from circuit, and releasable restraining means for said former means, said restraining means including a fusible element releasably secured within said device but adjacent a working surface thereof for subjecting said fusible member to the thermal conditions of said working surface, said device having an opening therein to render said element accessible from the exterior thereof for removal and renewal.

4. The combination with an electrically heated device, of circuit control means therefor tending to disconnect the same from circuit, said device having an opening in a surface thereof and a shoulder adjacent to said opening, a fusible element to fit within such opening, and a member secured to a fusible part of said element and to said circuit control means to provide for retention of said fusible element in cooperative relation with said shoulder and for restraint of said circuit control means subject to release thereof through fusion of said element under predetermined thermal conditions of said surface of said device.

5. The combination with an electrically heated device, of circuit control means for said device tending to disconnect the same from circuit and restraining means for said former means including a body of fusible material located adjacent a working surface of said device and accessible from without said device and means extending through and beyond said device for connecting said circuit control means with said body of fusible material subject to release upon fusion of the latter.

6. The combination with an electrically heated iron, of circuit control means located upon the top thereof tending to disconnect said iron from circuit and restraining means for said former means including a body of fusible material releasably secured adjacent the working surface of said iron and means extending through said iron for connecting said circuit control means with said fusible material.

7. The combination with an electrically heated device, of circuit control means therefor tending to disconnect the same from circuit and a fusible connection between said control means and said device, said connection including a fusible element located within said device and accessible from a working surface of said device for removal or renewal.

8. The combination with an electrically heated device having means operable to disconnect the same from circuit, of

means tending to so operate the former means, and a fusible element for restraining the second mentioned means subject to release upon fusing of said element, said heated device having a socket therein and said element being readily insertible into and removable from said socket.

9. The combination with an electrically heated device having means operable to disconnect the same from circuit, of means tending to so operate the former means, and a fusible element for restraining the second mentioned means subject to release upon fusing of said element, said device having a socket therein adjacent to a heated working portion thereof and said element being detachably secured to said device and having its fusible material arranged to be located within said socket.

10. The combination with an electrically heated device having means operable to disconnect the same from circuit, of means tending to so operate the former means, and a fusible element comprising a reciprocatory restraining member for the latter means and a member releasably secured within a portion of said heated device, said members being releasable for relative separation through fusing action subject to the thermal conditions of said heated device.

11. The combination with an electrically heated device having means operable to disconnect the same from circuit, of means tending to so operate the former means, and releasable restraining means for said latter means comprising an annular fusible member to be secured to said device, a reciprocatory member engaging said first mentioned means and extending within said annular member and secured thereto, subject to release through fusion thereof.

12. The combination with an electrically heated device having means operable to disconnect the same from circuit, of a spring tending to so operate said means, and thermally releasable restraining means for said spring comprising an annular member retained within a socket in said heated device, a reciprocatory rod engaging said spring substantially at right angles and extending within said member, said member being composed of fusible material subjected to the thermal conditions of said device for insuring release of said rod upon undue heating of said device.

13. The combination with an electrically heated device having means operable to disconnect the same from circuit, of a spring tending to so operate said means, and thermally releasable restraining means for said spring comprising a reciprocatory rod engaging the latter substantially at right angles and secured to said device by means of a fusible member located within a heated

portion of said device and adapted to soften 65 and release said rod upon undue heating of said device.

14. The combination with an electrically heated device having means operable to disconnect the same from circuit, of a spring 70 tending to so operate said means and thermally releasable restraining means for said spring including an annular member composed of fusible material held within a socket adjacent a heated portion of said device and a reciprocatory rod having one end secured to said spring and its opposite end extending through said annular member and headed therebeyond.

15. The combination with an electrically 30 heated device having means operable to disconnect the same from circuit, of a spring tending to so operate said means and thermally releasable restraining means for said spring including a reciprocatory rod having 35 one end adjustably engaging said spring substantially at right angles, the opposite end of said rod having a head, and an annular member composed of fusible material surrounding said rod adjacent said head 90 and being held within a shouldered socket adjacent a heated portion of said device by the tension of said spring, said rod and spring being releasable through softening of said fusible member upon undue heating 95 of said device.

16. The combination with an electrically heated device having means operable to open the circuit thereof, of means tending to so operate the former means and releasable restraining means for said latter means comprising a hollow member to be secured within a socket in said device and located adjacent a heated portion thereof, a reciprocatory member engaging said operating means and extending within said hollow member, said reciprocatory member being normally secured to said hollow member subject to release of the former upon undue heating of said device.

17. The combination with an electrically heated device having means operable to interrupt circuit therethrough, of a spring tending to so operate said means, and thermally releasable restraining means for said spring comprising a fusible medium held within a socket in said heated device and subjected to the thermal conditions of the latter, a reciprocatory rod engaging said spring substantially at right angles and normally restrained by said fusible medium, the latter being adapted to soften and release said member upon undue heating of said device.

In witness whereof, I have hereunto subscribed my name.

EDWIN N. LIGHTFOOT.
